GRAINING MACHINE

Bernard R. Halpern, New York, N. Y., assignor to
Charles Zarkin, New York, N. Y.

Application July 30, 1948, Serial No. 41,499

7 Claims. (Cl. 51—6)

1

The invention here disclosed relates to graining machines of the types covered by Zarkin Patents 1,718,020, 1,935,306, 2,074,633, 2,413,898 and 2,413,899 and Metrick Patent 1,960,447, wherein the tub is supported on ball bearings carried by the base of the machine and controlled by a so-called "diamond frame" mounted to slide on the base in one direction and having sliding connection with the tub at right angles to that direction.

Special objects of the present invention are to improve the mounting of the tub on the base, the operation of the guiding or control frame between the base and tub and the smooth, quiet running operation of the machine as a whole.

Particular objects also are to simplify and improve the construction and operation of the dumper and the drive connections from the motor which serves to operate the tub and to drive the pump which supplies the hydraulic power for operating the dumper.

Other special objects of the invention are to improve the plate hold-down clamp structure and mounting and the retention and control of the marbles in and the discharge of the same from the graining tub.

Objects of the invention also are to improve the general appearance of the machine and to provide safety enclosure for the various operating parts of the machine.

Other desirable objects attained by the invention are indicated or will appear in the course of the following specification, wherein the novel features of the invention are definitely set forth and broadly claimed.

The drawings accompanying and forming part of the specification illustrate a present commercial embodiment of the invention. The structure, however, may be modified and changed as regards this present illustration, all within the true intent and scope of the invention as hereinafter defined and claimed.

Fig. 1 is a front elevation of the machine, with enclosed portions indicated in broken lines;

Fig. 2 is a top plan view of the same;

Fig. 3 is a broken part sectional end elevation of the complete machine;

Fig. 4 is a broken part sectional front elevation of the main operating parts of the machine, with broken lines indicating the tub in partly raised relation;

Fig. 5 is a top plan view of the base or main frame with the graining tub and control frame removed;

2

Fig. 6 is a horizontal sectional view as on substantially the plane of line 6—6 of Fig. 4;

Fig. 7 is an enlarged broken sectional detail of the discharge door structure at the end of the tub, including the discharge spout and stationary chute;

Fig. 8 is a broken plan view of the main working portions of the machine;

Fig. 9 is an enlarged broken sectional view of the tub bearings and guide or control frame;

Fig. 10 is an enlarged broken sectional detail of one of the plate hold-down clamps;

Fig. 11 is another broken sectional view of a hold-down clamp locked up in raised position, this view being taken on a plane at right angles to the plane of Fig. 10; and

Fig. 12 is a detail view of one of the clamp blocks for securing the ends of the clamp supporting cross bar.

As shown in Figs. 1, 2 and 3, all working parts of the grainer, including the tub 15 and dumper 16, are enclosed within a cabinet 17 attached to and carried by the base forming portion 18 of the machine.

The top of the cabinet is made up of large, full width doors or covers 19, 20, hinged at 21, 22, so that they can be raised and thrown back to fully expose the tub and dumper.

The front of the cabinet is shown as having doors 23, 24, which can be swung open on hinges at 25, 26, to expose operating parts, and door 24 particularly to provide access to the drain tank 27 for the dumper, slidingly mounted on cross rails 28 so that it may be pulled out for cleaning or other purposes. To permit such removal this tank is shown as having a detachable coupling 29 at the back of the cabinet with the drain or sewer connection 30.

A valve 31 at the front of the cabinet controls admission of water from a supply pipe 32 to a spray pipe 33 across the head of the tub for plate rinsing or other purposes, a looped length of hose 34 being interposed between the tub and supply valve to allow for the lifting and lowering and graining movements of the tub.

A starting and stopping switch 35 is shown mounted on the front of the cabinet and exposed control handles 36, 37, for controlling the lifting and lowering operations of the dumper and tub, respectively.

This complete enclosure of all operating portions of the grainer affords protection to the operators and is a protection to the machine as well. This enclosure may be of a soundproof character to keep the operation as quiet as pos-

sible. While completely enclosed during normal graining operations, the action may be immediately inspected at any time on lifting the top covers or opening the front doors. The top covers will swing back into fully supported reversed relation on the stationary top panels 38 at the ends of the cabinet, in which relation the tub may be fully lifted and the dumper be operated to remove or to replace the marbles or other graining elements or materials.

This fully enclosed or cabinet type machine is particularly well adapted for airborne transportation, as required in army service.

In the further carrying out of this purpose all parts are grouped and related as compactly as possible and are made as light in weight as consistent with required strength and most effective results.

In the machine illustrated the tub 15 is made of light metal such as aluminum, lined with a protective layer of rubber or the like, hinged at 39 on one end of the sub-frame 40 and adapted to be raised by a hydraulic jack 41 at the opposite end of the sub-frame, a spring 42 being connected between this end of the tub and the sub-frame to pull the tub, when light, downward against any frictional resistance present in the jack or other connections.

To guide the tub in its lifting and lowering movements and to brace it in its lifted relation and take lateral loads off the hinge 39, the tub is shown as having dependent guides 43 at opposite sides near the upper end of the same to ride over the opposite side edges of the sub-frame and to remain in engagement therewith even in the fully uplifted position.

The tub is supported on the main frame or base 18 by self-aligning bearings consisting of a set of three ball cups 44, 45, 46, mounted in triangular relation on top of the main frame and carrying the balls 47 on which the bearing plates 48 at the under side of the sub-frame ride.

In the illustration one bearing, 44, is located at one end of the main frame and the two other bearings, 45, 46, are located at the opposite end of the main frame, in this case the hinge end of the tub where most of the load may be concentrated in the tilting movements of the tub.

This self-aligning, three-point bearing is of great advantage in the manufacture and maintenance of the machine, since no problems of misalignment are present and the load is always substantially uniformly distributed, with automatic equalization for wear as it occurs. This three bearing construction also is lighter and less expensive than the four bearing structures heretofore used, eliminating need for machining the ball cup pads for leveling.

The self-aligning, three-point bearing advantages are also incorporated in and carried out in the guide or control frame structure.

In the machine illustrated the control frame 49 is shown as of generally triangular structure having three dependent guide rolls 50, 51, 52, at the approximate corners of the same sliding in guides 53, 54, 55, on top of the main frame. The first two sets of these guide bearings 50—53 and 51—54, are shown located at opposite sides of the single tub bearing 44 at one end of the machine and the single slide bearing 52—55 at the opposite end of the main frame between the pair of tub bearings 45, 46, the triangular relation of the two sets of bearings being thus reversed to provide a compact structure and more or less equalize and distribute the various bearing loads.

The connections between the control frame and tub are shown as projecting guide rolls 56, 57, on top of the frame engaged in aligned guides 58, 59, on the bottom of the tub sub-frame. These two last mentioned guides are shown in Fig. 8 disposed on a line between the guides at opposite ends of the triangular control frame and approximately in line with the vertical drive shaft 60 of the machine.

The shaft 60 carries a crank or eccentric 61 at its upper end engaging a bearing 62 on the under-side of the tub sub-frame and is shown as carrying a counter-weight 63 having a removable segmental portion 64 at the outer rim, of a size and positioned to match as closely as possible the center of mass of the tub. This construction also locates the counter-weight in compact relation, substantially at the level and within the outline of the guide frame 49.

Further carrying out the idea of compactness, few parts and light weight, a single direct drive is provided for both the tub and the pump which furnishes the hydraulic pressure for lifting the tub and operating the dumper. This drive is shown as a single V-belt connection 65 running from the pulley 66 on the motor 67, located at one end of the main frame around opposite sides of the large pulley 68 on the lower end of shaft 60, about the smaller pulley 69 on the pump 70 at the opposite end of the main frame.

The pulleys 68 and 69 are proportioned to provide the desired gear reduction to the graining tub and to the pump, respectively, and this relation, as shown in Fig. 6, provides sufficient wrap of the belt about all three pulleys for efficient drive from the motor to both the tub and the pump.

The motor is shown mounted on a panel 71 extending across the end of the main frame hingedly supported at one end as by means of spring loaded bolt fastenings 72, sufficiently loose or adapted to be loosened to permit the opposite end of the panel to be swung outward away from the supporting frame, as by means of pressure applying hand screws 73 bearing against the end of the frame. This provides a simple, direct, single adjustment for taking up slack and adjusting belt tension on all three pulleys 66, 68 and 69.

The triangular guide frame 49 is shown as riding on rollers 74 operating in grooves 75 at the sides of the guide grooves 76 in the guide plates 53, 54, 55. These small rollers 74 carry the vertical loads on the reciprocating guide frame and keep it in smooth, quiet running operation.

Lubrication of the main working parts is provided for in the illustration by grease gun fittings 77 on the front of the main frame, having connections 78 extending to the ball cups 44, 45, 46, and similar fittings 79 on the front of the control frame 49, having connections 80 extending to the downwardly and upwardly projecting guide rollers on that frame.

The tub is shown as having a dumping door 81 at its lower or hinge end carried by a hinge rod 82 provided with an outwardly projecting lever arm 83 engaged by the upper end of a spring link 84 which has its lower end pivotally connected at 85 with an arm 86 extended out from the sub-frame. This link is tensioned to pull down on the lever arm 83 to hold the door closed in the lowered or normal operating position of the tub and to operate as a strut to rock the

5

door open automatically as the tub is raised to discharge the marbles.

To properly confine the released marbles, the door opening in the end of the bottom portion of the tub is shown substantially surrounded by an outwardly projecting, downwardly inclined spout 87. This discharges into the downwardly inclined stationary chute 88 which serves to open the trap-door 89 in the wall of the dumper, as the latter is lowered in the manner disclosed in the earlier issued patents identified.

The dumper 16 is shown as carried by arms 90 having sleeves 91 aligned over the ends of bearing sleeves 92 fixed on supporting arms 93 projecting from the end of the main frame, the parts being hingedly connected in this relation by a tubular hinge rod 94 inserted through the aligned sleeves.

The hydraulic ram 95 for operating the dumper is shown pivoted at 96 on a bracket or step 97 at the end of the main frame.

To prevent any drip from the tub or discharge spout dropping down on the motor or belt drive connections, an inclined panel 98 is shown projecting from the end of the main frame over the top of the motor.

The tub is shown as constructed with inwardly extending stiffening flanges 99 about the upper edges of the same. These may act as retainers for the graining balls and they are utilized also in the present disclosure as supports for the cross bars 100 which carry the plate holding clamps.

These bars are shown as of T cross section and disposed each with the stem portion 101 of the T resting flat on the tub flanges 99 and the head forming flanges 102, 103, of the T disposed vertically for engagement by the vertically opposed jaw portions 104 of the clamps.

The lower flanges 103 of the cross bars are shown cut back at 105 to engage the edges of the tub flanges to center and hold the bars against longitudinal displacement, and the upper flanges 102 are shown cut back at 106 to permit endwise sliding engagement of the holding jaws 104 of the clamps over such flanges.

The bars are shown as adjustably secured at any selected positions along the length of the tub by clamp blocks 107 engaging the undersides of the tub flanges 99 and secured by hand screws 108.

The clamps are shown as having plunger portions 109 sliding in the tubular guide portions 110 and pressed downwardly by enclosed springs 111. Beveled pads 112 of rubber or other suitable material on the lower ends of the plungers afford firm holding engagement of the plates.

The downward spring pressure of the clamps, through reaction against the cross bars, holds these clamps yieldingly in position.

To facilitate the release and easy shifting of the clamps, they are shown as having thumb buttons or projections 113 on the plungers 109 operating through bayonet slots 114 in the tubular guide portions 110. These buttons may be lifted to take the pressure of the pads off the plate and then upon turning the buttons over the shoulders 115 at the upper ends of the bayonet slots, the holding pads or feet may be locked back in the lifted or retracted position, free of the plate and with the clamps free of holding tension against the supporting bar, all as shown in Figs. 10 and 11.

What is claimed is:

1. A graining machine comprising a base, a

6

graining tub, a set of three ball bearings arranged in triangular relation on said base and supporting said tub for graining movements on the base, a control frame between the tub and base mounted to slide in one direction on the base and having a sliding connection with said tub in a direction at right angles to said first direction and a rotary drive connection to said tub.

2. A graining machine comprising a base, a graining tub, a set of three ball bearings arranged in triangular relation on said base and supporting said tub for graining movements on the base, a control frame between the tub and base mounted to slide in one direction on the base and having a sliding connection with said tub in a direction at right angles to said first direction and a rotary drive connection to said tub, said control frame having three sliding guide connections with said base arranged triangularly and oppositely to the triangular relation of the three tub bearings on the base.

3. A graining machine comprising a base, a graining tub, a set of three ball bearings arranged in triangular relation on said base and supporting said tub for graining movements on the base, a control frame between the tub and base mounted to slide in one direction on the base and having a sliding connection with said tub in a direction at right angles to said first direction and a rotary drive connection to said tub, said control frame being of generally triangular shape and having sliding connections with the base at the three corners of the same.

4. A graining machine comprising a base, a graining tub, a set of three ball bearings arranged in triangular relation on said base and supporting said tub for graining movements on the base, a control frame between the tub and base mounted to slide in one direction on the base and having a sliding connection with said tub in a direction at right angles to said first direction and a rotary drive connection to said tub, said tub bearings being arranged two at one end of the base and the third at the opposite end of the base, said tub having a sub-frame on which it is hinged at that end where the two tub bearings are located.

5. A graining machine comprising a base, a graining tub, a set of three ball bearings arranged in triangular relation on said base and supporting said tub for graining movements on the base, a control frame between the tub and base mounted to slide in one direction on the base and having a sliding connection with said tub in a direction at right angles to said first direction and a rotary drive connection to said tub, two of said tub bearings being located at the corners of the base at one end and the third bearing being located intermediate the corners at the opposite end of the base and said control frame being of substantially triangular formation with one slide connection with the base disposed between the two tub bearings at one end of the base and having two other slide connections with the base at opposite sides of the single tub bearing at the opposite end of the base.

6. A graining machine comprising a base, grooved guides on said base, said guides having parallel grooves at the sides of the guide grooves therein, rollers free to turn in said parallel grooves, a control frame riding on said rollers and having rollers riding in said guide grooves, a tub mounted for graining movements on the base over said frame, control connections between said frame and tub and lubricating con-

nections extending from the frame at one side to said guide rollers.

7. A graining machine comprising a base, grooved guides on said base, said guides having parallel grooves at the sides of the guide grooves therein, rollers free to turn in said parallel grooves, a control frame riding on said rollers and having rollers riding in said guide grooves, a tub mounted for graining movements on the base over said frame, control connections between said frame and tub, ball cups on said base, balls rolling in said cups for supporting the tub and lubricating connections extending to said ball cups and to said guide rollers on the control frame.
